PANTS HANGER

Ray Hultsch, Melrose Park, Ill.

Application May 14, 1945, Serial No. 593,673

4 Claims. (Cl. 223—96)

1

This invention relates to a pants hanger, and more particularly to a pants hanger adapted to support a garment such as a pair of pants in suspended position.

A primary object of this invention is the provision of an improved pants hanger characterized by a pair of oppositely disposed supporting members adapted to be inserted within the cuffs of the trouser legs and separated in such manner as to align the opposite creases of both legs of the pair of trousers and support the garment from an internal position, thus obviating the marks normally left on such garments by hangers of conventional types.

An additional object of the invention is the provision of such a device which may be readily associated with, or disassociated from, a pair of trousers with a minimum of effort and difficulty.

Still another object is the provision of such a device which may be readily adjusted to accommodate trousers having cuffs of varying widths.

Other objects reside in the provision of such a device which will be sturdy and durable in construction, reliable and efficient in operation, and relatively simple and inexpensive to manufacture and assemble.

Other objects will in part be obvious and in part be pointed out as the description of the invention proceeds, and shown in the accompanying drawings, wherein there is disclosed a preferred embodiment of this inventive concept.

In the drawings:

Figure 1 is a side elevational view of one form of device embodying features of the instant invention, certain concealed portions thereof being indicated in dotted lines.

Figure 2 is a view similar to Figure 1 viewed from the opposite side of the device.

Figure 3 is a view similar to Figure 1, but showing certain of the operating parts in different positions of adjustment.

Figure 4 is an enlarged sectional view taken substantially along the line 4—4 of Figure 1 as viewed in the direction indicated by the arrows.

Figure 5 is an enlarged sectional view taken substantially along the line 5—5 of Figure 1, as viewed in the direction indicated by the arrows.

Figure 6 is an enlarged sectional view taken substantially along the line 6—6 of Figure 1, as viewed in the direction indicated by the arrows.

Figure 7 is an enlarged sectional view taken substantially along the line 7—7 of Figure 1, as viewed in the direction indicated by the arrows.

Similar reference characters refer to similar parts throughout the several views of the drawings.

Having reference now to the drawings, there are disclosed at 10 and 11 a pair of plate-like members normally positioned in slidable horizontal alignment, and each provided at one end

2

with a depending fork-like member 12 and 13, respectively, and at its opposite end with a clip 14 and 15, respectively, each of the clips 14 and 15 comprising, as best shown in Figure 7, a channel-shaped member adapted slidably to embrace the opposite bar or plate, the arrangement being such that the bars are free to slide in substantially parallel relation with each other.

Each of the clips 14 and 15 is secured to its associated plate, as by means of rivets 16 and 17, respectively, and each takes the form, as best shown in Figure 7, of a substantially channel-shaped portion adapted to embrace the oppositely positioned plate-like member.

15 A clip member 20 is slidably positioned on the member 10 and is of substantially channel-shaped cross section adapted to embrace the member 10, the inwardly turned flanges 21 of the clip being adapted to be positioned between the members 10 and 11. The clip 20 is provided, as best shown in Figure 6, with a threaded aperture 22 through which extends a set screw 23 provided with a knurled head 24, the arrangement being such that the extremity of the set screw engages the side of the plate member 10 to secure the clip in 20 adjusted position therealong. An extending link 25 is pivotally secured, as by a pivot 26, to an extremity of the clip 20 and has its opposite end pivotally secured, as by means of a pivot 27, to a lever 28 terminating in a hook 29. The opposite end of the lever 28 is pivotally secured, as by means of a pivot 30 to the plate-like member 11 at a point between the members 10 and 11.

The clip 20 is provided with an upwardly extending lug 31 having an aperture 32 therein to 35 which is secured one end of a coil spring 33, the opposite end of which is secured as in an aperture 34 in a point on the lever 28 between the pivot 27 and the pivot 30.

40 From the foregoing, the operation of the device should now be readily understandable. When it is desired to utilize the device for the hanging of a pair of trousers, the fork members 12 and 13 are first adjusted to the proper width of the trousers by loosening the set screw 23 by means of a knurled knob 24 and sliding the members 10 and 11 outwardly with respect to each other until the fork members 12 and 13 seat snugly, but not tightly, within the interior of the cuffs of the trousers.

45 The set screw 23 is then tightened and the device is ready for operation. It will now be seen that compression of the lever 28 serves to draw the fork members 12 and 13 toward each other through the relative shifting of the plates 10 and 11, it being noted that the lever 28 is pivotally secured to the member 11, while the associated link 25 is in effect pivotally secured to the member 10 through the fixed connection between the clip 20 and the plate member 10. Thus, when the member 28 is released and the device supported,

55

as by means of the hook 29, the natural weight of the garment in addition to the bias exerted by the spring 33 serves to separate the fork members 12 and 13 exerting a firm pressure outwardly against the cuffs of the trousers, and thus firmly supporting the trousers in suspended position.

From the foregoing, it will now be seen that there is herein provided a device accomplishing all the objects of the invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. A garment stretching and suspending device comprising a longitudinally extensible member consisting of a pair of flat, elongated strips disposed in parallel juxtaposition, garment attaching means carried by the outer end of each strip, a clip means secured at the inner end of each strip and embracing the other strip in sliding, guiding and retaining relation, and stretching means pivoted and adjustably secured to said strips for longitudinally extending and retracting said strips, said stretching means including a lever pivoted terminally to one of said strips, a link pivoted at one end intermediately of said lever and at the other end pivoted to the other strip and having its pivot adjustable longitudinally thereof.

2. A garment stretching and suspending device comprising a longitudinally extensible member consisting of a pair of flat, elongated strips disposed in parallel juxtaposition, garment attaching means carried by the outer end of each strip, a clip means secured at the inner end of each strip and embracing the other strip in sliding, guiding and retaining relation, and stretching means pivoted and adjustably secured to said strips for longitudinally extending and retracting said strips, said stretching means including a clamp adjustably secured to one strip, a lever pivoted to said other strip and a link pivoted to said lever and to said clamp.

3. A garment stretching and suspending device comprising a longitudinally extensible member consisting of a pair of flat, elongated strips disposed in parallel juxtaposition, garment attaching means carried by the outer end of each strip, a clip means secured at the inner end of each strip and embracing the other strip in sliding, guiding and retaining relation, and stretching means pivoted and adjustably secured to said strips for longitudinally extending and retracting said strips, said stretching means including a clamp adjustably secured to one strip, a lever pivoted to said other strip and a link pivoted to said lever and to said clamp, said clamp being slidably disposed upon one strip and locking means for securing said clamp in selective position thereon.

4. A garment stretching and suspending device comprising a longitudinally extensible member consisting of a pair of flat, elongated strips disposed in parallel juxtaposition, garment attaching means carried by the outer end of each strip, a clip means secured at the inner end of each strip and embracing the other strip in sliding, guiding and retaining relation, and stretching means including a clamp adjustably secured to one strip, a lever pivoted to said other strip and a link pivoted to said lever and to said clamp, and a spring means secured to said clamp and to said lever and normally biasing said strips into collapsed position.
